[57] **CLAIM**

The ornamental design for a lamp head for an adjustable task light, as shown and described.

DESCRIPTION

FIG. 1 is a top, front perspective view of a lamp head for an adjustable task light showing our new design;

FIG. 2 is a top plan view thereof;

FIG. 3 is a left side elevational view thereof relative to the front of the lamp;

FIG. 4 is a right side elevational view thereof relative to the front of the lamp;

FIG. 5 is a front elevational view thereof;

FIG. 6 is a rear elevational view thereof; and,

FIG. 7 is a bottom plan view thereof.

The articulated arm is shown in broken lines for illustrative purposes only and form no part of the claimed design.

FIG. 1.

FIG. 2.FIG. 3.FIG. 4.FIG. 5.FIG. 6.FIG. 7.
